PAY OUT REEL

Frank Stasio, Corry, Pa.

Application May 14, 1941, Serial No. 393,431

3 Claims. (Cl. 242—114)

This invention relates to a reel for use in holding a bundle of wire as it is being fed to a spring making machine, for winding a bundle on, for flat stock, etc.

The invention especially enables quick change from one bundle to another in order to save time, and it aims to accommodate any size bundle and to provide accordingly a construction which is adjustable, self-centering, and one in which the bundle of wire automatically centers itself to make a smooth running reel.

The more specific objects and advantages will become apparent from a consideration of the description following taken in connection with accompanying drawing illustrating an operative embodiment.

In said drawing:

Figure 1 is a view in side elevation of the structure;

Figure 2 is a plan view thereof;

Figure 3 is an enlarged vertical section taken on the line 3—3 of Figure 2, and

Figure 4 is a horizontal section taken on the line 4—4 of Figure 3.

Referring specifically to the drawing wherein like reference characters designate like or similar parts, a cast iron or other relatively heavy base is provided at 10 adjustably and detachably mounting a reel standard 11 at a hub 12, fastened in place by a screw 13.

The standard 11 has a reduced portion 14 at the upper extremity, providing a shoulder at 15.

The reel is generally designated 16, having a hollow hub 17, which is journaled on the reduced portion 14 and rests on the shoulder 15. Such hub 17 has a removable cover or closure 18 screwed in place as at 19.

The reel also has an outer ring 20 and such ring and hub 17 are rigidly connected together by means of rods or spokes at 20a.

Screw shafts 21 and 22 have their ends journaled in the hub 17 and in bearings 21a depending from the ring 20, the screw threads of the screws 21 preferably being right hand and those of the screws 22 preferably being left hand. Upright arms 23 are screw threaded one on each screw 21 and 22 and the rods 20a pass therethrough so as to hold the arms in upright positions. Extension arms 24 are pivoted or bolted at 25 to the arms 23.

The outer end, of each of the screw members 21 and 22, projects beyond the outer ring 20 and is shaped into a wrench engaging head 26 whereby the same may be detachably engaged by a wrench or crank 27, as suggested in Figure 1.

Within the hub 17, beveled gears 28 are keyed one to each screw member 21 and 22 and all are enmeshed as best shown in Figure 4.

In using the device, the wire is laid on and supported by the rods 20a outwardly of the arms 23. Any one of the screw members 21 and 22 may be turned by the crank 27, in order to simultaneously turn all of such members and thereby simultaneously and to the same extent move the arms 23 outwardly into engagement with the wire. Likewise to release the wire the crank may be turned in the opposite direction to move the arms inwardly. The auxiliary or extension arms 24 may be moved to any desired angle with a view to aiding in retaining the wire on the arms 23.

Various changes may be resorted to provided they fall within the spirit and scope of the invention.

I claim as my invention:

1. A structure of the class described comprising a standard, a reel swivelled on the standard comprising a hub, screw members mounted by the hub, interengaged gearing carried by the screw members at the hub, wire engaging arms movably mounted by the screw members, an outer ring in which the screw members are journaled, and rods connecting the hub and outer ring passing through the arms to maintain the latter upright and also serving to support wire.

2. A structure of the class described comprising a standard, a reel swivelled on the standard comprising a hub, screw members mounted by the hub, interengaged gearing carried by the screw members at the hub, wire engaging arms movably mounted by the screw members, an outer ring in which the screw members are journaled, rods connecting the hub and outer ring passing through the arms to maintain the latter upright and also serving to support wire, bearings connected to the outer ring in which the screw members are directly journaled, one of the screw members having a tool engaging end to facilitate rotation thereof, and a support for the standard.

3. A structure of the class described comprising a reel having a hub, screw members mounted by the hub, interengaged gearing for the screw members at the hub, wire engaging arms movably mounted by the screw members, an outer ring in which the screw members are journaled, and rods connecting the hub and outer ring passing through the arms to maintain the latter upright and also serving to support wire.
